EXPLOSIVE CARTRIDGE

Louis R. Triscoli, Southampton, Hollis L. Muller, Jr., York Springs, and Thomas Q. Ciccone, Langhorne, Pa., assignors to the United States of America as represented by the Secretary of the Army

Filed July 18, 1957, Ser. No. 672,843

1 Claim. (Cl. 102—39)

(Granted under Title 35, U.S. Code (1952), sec. 266)

The invention described herein may be manufactured and used by or for the Government for governmental purposes without the payment of any royalty thereon.

Our invention relates to explosive cartridges such as are utilized to actuate the ejection mechanism of aircraft, and has for its principal object the provision of an improved cartridge wherein the primer is more effectively shielded from any desensitizing effect of the propellant and there is provided a seal which obviates the need of the aluminum disk formerly used to complete the seal between the casing and head of the cartridge. It is a further object of our invention to so form the sealed end of the cartridge that a mechanical device containing a firing pin may be accurately brought into cooperative relation with the primer of the cartridge.

Our invention will be better understood from the following description considered in connection with accompanying drawings and its scope is indicated by the appended claims.

The single figure of the drawing illustrates a cartridge of the above type having a metal casing 10 which encloses a double-base propellant 11. Adjacent the propellant 11 is a membrane 12 which is an integral part of a head member 14 which is made of aluminum and forms a closure for the head end of the cartridge. Nested within the aluminum head member 14 is a primer-ignition cup 13.

In making the seal between the casing 10 and the closure 14, a coating of Thiokol base adhesive or the like is applied between the contiguous surfaces of these members and the top of the casing is forced into a groove 15 and up over a rounded shoulder of the member 14. A shoulder 16 is so formed as to guide an external mechanism, which includes a firing pin, into operative relation with the cartridge as hereinafter explained.

The seal between the casing 10 and the member 14 has the important advantage that it omits the usual aluminum disk and O-ring of the prior art seal. In the use of this prior art seal, it has been found that the aluminum disk absorbed a large proportion of the energy delivered from the firing pin. The delivered energy, in the case of some mechanical devices, has been found to be marginal so that any further loss may result in unreliability of the cartridge. The omission of the aluminum disk results in a significant increase in sensitivity and reliability. Fur-

2

thermore, the use of the prior art seal causes a change in firing pin dimension which affect primer reliability. This is due to the fact that since the firing pin does not pierce the aluminum disk the .005" thickness aluminum disk joins the firing pin and together the total effect is delivered to the primer. Since the firing pins are designed with a specific dimension, this change can amount to as much as .010" and has decidedly detrimental effect on the reliability of the primer performance.

10 The use of the prior art cartridge with an external mechanism including a firing pin involved the difficulty that there always existed the possibility of eccentricity between the firing pin and the primer. This had an adverse effect on the functioning of the primer sometimes resulting in misfiring. This difficulty is avoided by so forming the upper surface of the closure 14 that the firing pin and its associated mechanism (indicated by the reference numeral 17) are guided into a position where the firing pin is properly related to the primer.

15 20 Our invention thus provides an improved cartridge wherein the adverse effect of the propellant on the primer is avoided, sensitivity and reliability are increased, and a cooperative relation between the primer and firing pin is ensured.

25 We claim:

An explosive cartridge of the type for actuating ejection mechanism of an aircraft and having a metal case closed at one end and closed at its opposite end by a metal head member of larger diameter at least in part than is the major portion of said case and around which said case is fitted, a double base propellant in said case between said head member and its closed end, a primer cup within said head member in its larger diameter portion, a metal membrane between said primer cup and propellant and integral with said metal head member, said head member and membrane being of one piece, said head member having an open recess outside of said primer cup but contiguous thereto and of larger diameter than said primer cup and larger than the radius of said head member for guiding reception of a firing pin mechanism into axial alignment with said primer cup, the outer edge of said metal head outside said open recess being radially and longitudinally inwardly bevelled and an outer end of said case being bent over said outer edge of said head, whereby any gas from said propellant will pass between the head and case and leak into the air rather than get into the primer cup and whereby a danger of misfire from eccentricity of the firing pin and its mechanism is reduced.
